UNITED STATES PATENT OFFICE.

WALTER G. STEWART, OF READING, PENNSYLVANIA.

DUMPING-WAGON.

SPECIFICATION forming part of Letters Patent No. 539,094, dated May 14, 1895.

Application filed June 18, 1892. Serial No. 437,162. (No model.)

To all whom it may concern:

Be it known that I, WALTER G. STEWART, a citizen of the United States, residing at Reading, in the county of Berks, State of Pennsylvania, have invented certain Improvements in Dumping-Wagons, of which the following is a specification.

This invention relates particularly to dumping wagons intended to deliver their contents through a chute, and consists in an improved lever mechanism for elevating the bodies thereof.

In a patent issued to me May 17, 1892, No. 474,872, I have described a dumping wagon in which a well known form of radius bar is employed as a main elevating arm, the opposite ends of which are pivoted respectively to the frame and to one end of the movable body, while the other end of the body is elevated by a separate lever mechanism operatively connected to the main arm. This radius bar connection causes that portion of the body to which it is pivoted to swing in the arc of a circle around the frame connection; and in practice this necessitates the use of a long arm in order to secure a high elevation without an objectionable amount of horizontal movement. This movement, which always results from the use of the form of elevating arm referred to, is commonly arranged to be rearward, thus bringing the load somewhat nearer the desired point of deposit; but the slight advantage resulting is far more than counterbalanced by the danger of upsetting the wagon backward if it is attempted to raise the body to any considerable elevation, and by the undue strain brought on the rear springs and axle. In my present invention I have had in view the changing of the construction so as to enable the body to be raised vertically, or with only a desired amount of horizontal movement, to a high elevation; and to accomplish this with a minimum amount of material.

The invention consists mainly in the novel construction and arrangement of the main elevating arm whereby its pivotal connection to the body may be maintained in substantially a vertical line above its pivotal connection to the frame during the operation of elevating the body; the said arm being formed as a toggle-lever the upper member of which

is extended and connected to a single-power mechanism, by means of which both members of the toggle-lever elevating arm are positively and simultaneously operated so as to cause a substantially vertical elevation of that portion of the body to which it is pivoted. The opposite portion of the body is operated by means of a lever mechanism which is arranged and automatically operated in a manner similar in the main to that indicated in my prior patent referred to.

Figure 1 is an elevation of a portion of a dumping-wagon embodying my invention, the full lines showing the body raised to a considerable height and the dotted lines indicating a lower position. Fig. 2 is a similar view illustrating several slight modifications. The normal position of the body upon the frame is indicated by dotted lines.

The drawings are mere diagram views indicating only those parts of the wagon with which my invention is directly connected.

A represents the movable body, and B the frame upon which it normally rests.

G indicates the ordinary transverse winding shaft which is mounted upon the frame B and operated by means of the usual crank and gearing, not shown, and J indicates a position for the rear axle.

The main elevating arm is made up of two parts or members C and C' which are jointed together at c and have their opposite ends c' and b pivoted respectively to the body A and frame B,—thus forming a toggle lever. When the body rests upon the frame B the pivotal points c' and b of the arm C C' are brought close together and the members are nearly parallel. In raising the body above the frame the object is to produce a movement which will be the combined effect of swinging the member C' upward and forward around its pivotal connection b with the frame, and at the same time swinging the upper member C upward and rearward around the joint c, the position of which constantly varies on the arc X. In order to produce these two movements power must be positively applied to both of the members C and C'; and this I accomplish in a very simple and satisfactory manner by extending the upper member C beyond the joint c so that it reaches below and to the rear of the winding shaft G and connecting the

end d^2 of this extension d to the winding chain f . The turning of the shaft G to wind up the chain it will readily be seen tends both to positively lift the member C' and to swing 5 the member C upon its jointed end c thus lifting the forward end of the body in approximately a vertical line, the variations from which may be regulated as hereinafter described.

10 In order to raise the rear portion of the body I employ a lever mechanism substantially the same as is employed in my prior patent referred to. The bell crank lever E is pivoted at b' to the rear end of the frame B and its 15 upper end e^2 is connected to the body at a , by means of a link E' thus forming a second toggle-lever somewhat similar to the main arm $C C'$. The lower arm e of the bell crank is connected by a chain F to the extension d of 20 the main arm member C so that the raising of the latter by the operation of the winding shaft G causes the simultaneous elevation of the rear portion of the body. The position of the body indicated by dotted lines, in which 25 the front end only is raised, is provided for by merely allowing a desired amount of slack to the chain F so that the rear mechanism is not operated immediately by the movement of the main arm.

30 When the body A is lowered to its normal position upon the frame the extension d lies under and extends somewhat to the rear of the axle J . I prefer to arrange the winding shaft G to turn in the direction indicated by 35 the arrow in raising the wagon body, and to form the extension d with an edge d' adapted to ride upon the shaft G as I am thus enabled to positively regulate the relative swing of the members C and C' around their respective 40 pivotal centers c and b . By properly proportioning the lengths of the parts and their relative location and form I am thus enabled to effect the elevation of the body either vertically or with a forward or rearward movement, as may be desired. Both front and rear 45 are positively and automatically elevated, at any desired angle, by the continued operation of the crank and any elevated position is positively and automatically maintained during the dumping operation, no supplemental 50 operation either to vary the angle of the body or to lock it for dumping being required.

In Fig. 2 a construction slightly modified in several respects is indicated. The extension 55 d of the main arm member C is not formed to ride upon the winding shaft as in Fig. 1, the relative movement of the members C and C' upon their pivotal points being determined only by their proportions and location with 60 respect to the winding shaft and other parts. The bell-crank E instead of being connected

to the body A by means of a link E' is provided with a roller h which rides upon the body in elevating it; and the chain F' instead of being connected to the extension d as in 65 Fig. 1 is wound upon the shaft G in the same manner as is the main chain f , the relative diameters of the shaft at the winding points for the two chains being proportioned to the relative lengths of chain to be wound upon 70 them during the elevating operation. Instead of the chain F , Fig. 1, a slotted link may obviously be employed to connect the main arm to the rear arm E , as in my prior patent all-referred to. 75

Having thus fully described my invention, I do not limit myself to the exact construction indicated, but

What I claim is—

1. The combination with the frame or running gear and the winding shaft mounted thereon, of the movable body and the toggle-lever elevating arm $C C'$ having its extended upper member operatively connected to said winding shaft, substantially as set forth. 80

2. The combination with the frame or running gear and the winding shaft mounted thereon, of the movable body and the toggle-lever elevating arm $C C'$ having its upper member formed with an extension d connected 90 to said winding shaft and arranged to ride thereon during the elevating operation, substantially as and for the purpose set forth.

3. The combination with the frame or running gear and the movable body of the main 95 elevating arm $C C'$ forming a toggle-lever and arranged to lift directly one end of the body, and elevating mechanism for the opposite end of the body operatively connected to a portion d of said toggle-lever substantially as set 100 forth.

4. The combination with the frame or running gear and the movable body of separate toggle-lever elevating arms for the front and rear of said body respectively, and a single 105 power mechanism positively connected to both the front and rear arms, substantially as set forth.

5. The combination with the frame or running gear and the movable body, of the toggle-lever elevating arm $C C'$, a power mechanism connected to one member thereof so as to permit said member to be moved without moving the other member and a guide to control the relative swing of the members in elevat- 115 ing, substantially as set forth.

In testimony whereof I affix my signature in presence of two witnesses.

WALTER G. STEWART.
